UNITED STATES PATENT OFFICE

FRED A. RUMNEY, OF ALLSTON, AND ALBERT E. HUDSON, OF LYNN, MASSACHUSETTS,
ASSIGNORS TO UNITED SHOE MACHINEY CORPORATION, OF PATERSON, NEW
JERSEY, A CORPORATION OF NEW JERSEY

FASTENER-INSERTING MACHINE

Application filed September 17, 1925. Serial No. 56,947.

This invention relates to fastener-inserting machines and is illustrated herein as embodied in a machine for inserting blind or invisible eyelets.

5 In the manufacture of shoes, the term "blind eyelet" is applied to an eyelet having its flange lying upon the outer surface of the shoe upper, and with its barrel clenched between adjacent layers of the shoe upper so that the flange of the eyelet appears on the outside of the finished shoe. The term "invisible eyelet", on the other hand, is applied to an eyelet having its flange lying upon the lining or facing of the shoe, and with the 10 entering end of its barrel clenched between adjacent layers of the work so that the eyelet is not visible on the exterior of the shoe. The present invention is applicable to machines for inserting both blind and invisible eyelets.

15 As a matter of convenience it will be described herein with relation to the insertion of invisible eyelets with the understanding, however, that this is done without any intention of limiting the invention thereby.

20 United States Letters Patent No. 1,271,721, granted July 9, 1928, upon an application of Walter Shaw, disclose a fastener-inserting machine provided with an expansible setting tool comprising a plurality of relatively movable sections, each carrying a portion of the clenching surface of the tool. This expansible tool is arranged to receive an eyelet from the raceway of the machine and is thereafter inserted through a lacing hole in one or 25 more layers of the work, and then spread apart by an expander while its clenching surface is between the layers of the work so as to put the tool into clenching condition. With the tool thus expanded, the eyelet is 30 moved lengthwise of the tool and its entering end is split and clenched between adjacent layers of the work by the expanded clenching surface. After this the expansible tool is contracted and withdrawn from the work.

40 It is an object of the present invention to provide an improved fastener-inserting machine having an expansible setting tool of the type just described which will be organized to operate in a manner that, at the same time, 45 will insure the production of high-grade

work and will lengthen the life of the expansible setting tool, as compared with that of expansible setting tools heretofore used, by minimizing the danger of damage to the tool, for example by foreign material, particularly 55 chips punched from shoe stock, caught between the members of the tool and thus causing the tool to be sprung and broken.

60 In accordance with the foregoing, the expander provided for the purpose of spreading the expansible set to condition it for fastener-clenching is, in the illustrated machine, housed within a tubular punch and the punch and expander are moved together to feed the work from punching to fastener-65 inserting position, the punch being maintained in engagement with the work throughout the feeding movement and thus insuring that the hole punched in the work is brought accurately into alignment with the expansible 70 setting tool. In order to control the relative position of the clenching surface of the expansible setting tool and the layers of the work when the tool is expanded to clamp an eyelet, the illustrated machine is provided 75 with an improved abutment located closely adjacent to and surrounding the punch, its position at the time of the insertion and 80 clenching of each eyelet being controlled by a stop fixed against movement toward and from the work, but conveniently adjustable in accordance with the varying requirements 85 of different kinds of stock. This abutment is held away from the work during the feeding movement and is located at a predetermined 90 position during the clenching operation by said stop, thereby limiting movement of the stock as the eyelet is introduced and during the clenching operation without interfering with the proper action of the clenching tool. 95 During the return movement of the punch, preparatory to the punching of another hole in the work, this abutment is withdrawn from contact with the work. Further to assist in the accurate control of the stock and 100 the expansible setting tool, movement of the latter in the direction of the stock is positively limited, prior to the expanding of the set, and the expander is positively locked 105 against movement away from the set while 106

the set is brought to and maintained in expanded condition. To facilitate the introduction of the clenching tool both into the eyelet prior to the insertion of the eyelet into the work, and into the work prior to the actual clenching of the eyelet, the entering end of the expansible setting tool beyond its clenching surface is gradually reduced in diameter or tapered. Thus the illustrated setting tool 10 is provided with a substantially dome-shaped end, the clenching surface being made up by a series of facets formed upon the relatively movable members of the expansible setting tool and extending from the portion of maximum diameter in a direction away from the entering end of the setting tool.

To prevent damage to the expansible tool by the chips punched from the work, the illustrated expander is utilized also as a chip ejector, being spring-held so that it can yield during the punching operation and, as the locality of the punched hole passes beyond the punch block during the feed, springing forward and ejecting the chip. Still referring to the illustrated machine, the ejected chips are caught by a chip collector and conducted away by a suitable conduit so that the possibility of a chip being caught by the expansible setting tool and thereby damaging the tool, is eliminated.

Further to protect the expansible setting tool, means is provided for at least partially withdrawing the punch from the work before the setting tool is introduced. After the completion of the work-feeding movement, the punch is moved so that its punching end is located somewhat beyond the limit of movement of the expansible setting tool, preferably intermediate between the outer and inner surfaces of the layer of the work through which the eyelets are not to pass.

While the illustrated machine, which comprises a preferred embodiment of the invention, includes all the foregoing features, it should be understood that this is not in all cases essential and that at least some of the advantages of the invention may be attained by other mechanisms. Moreover, in various of its aspects, the invention is not limited to a fastener-inserting machine organized to insert invisible eyelets, but is of use in connection with other machines.

With the above and other objects and features in view, the invention will now be described in connection with the accompanying drawings and pointed out in the claims.

In the drawings,

Fig. 1 is a front elevation of a machine for inserting invisible eyelets, embodying the present invention;

Fig. 2 is a perspective view of the punching and eyelet inserting instrumentalities of the machine showing, also, a portion of their operating means;

Fig. 3 is a front view, partly in section,

showing the position of the parts at the conclusion of the punching operation;

Fig. 4 is a vertical section through the punch and associated parts illustrating the ejection of chips during the feeding operation;

Fig. 5 is a front elevation, partly in section, showing the parts at the conclusion of the clenching operation;

Fig. 6 is a vertical section on a larger scale showing the position of the punching and clenching instrumentalities at the conclusion of the clenching operation;

Figs. 7 and 8 are detail perspective views of parts of a stop mechanism which controls the position of the punch during the feeding and clenching operations;

Fig. 9 is an elevation of the expansible setting tool of the illustrative machine; and

Fig. 10 is a perspective view of a chip collector which is arranged to receive the chips punched from the work.

The illustrated eyeleting machine embodying the present invention has a sliding head carrying a punch operated by toggle mechanism to punch a hole in the work and then moved horizontally to feed the work to eyelet inserting position, the eyelet which is taken from a raceway then being introduced from below and clenched in the hole formed in the work by the punch. After this the punch is withdrawn from the work and moved horizontally in the reverse direction to complete the cycle of operation of the machine. An eyelet inserting machine of this type is shown in United States Letters Patent 1,228,768, granted June 5, 1917, upon an application of Perley R. Glass. Since machines of this type are well-known in the trade, it has not been considered necessary to make a detailed disclosure of all the mechanism of such a machine. For further details than those disclosed herein, reference may be made to said United States Letters Patent 1,228,768.

The illustrated machine, as best shown in Figs. 1, 2, 3 and 5, is provided with the usual work support 2, punch block 4, edge gage 6, and presser foot 8, as well as with a sliding head 10 guided in its reciprocating movements by a pair of rods 12 and 14. Mounted for reciprocating movement in the sliding head 10 is a punch bar 16 which is arranged for vertical movement by means of toggle mechanism 18, 20. A vertically reciprocated shaft 24 carries a hollow eyelet supporting tool 26 with a conical top 27 arranged to support the flange of an eyelet. Telescopically mounted within the supporting tool 26 is an expansible spindle and setting tool 28 arranged, as shaft 24 is moved upwardly, to pick an eyelet from the end of a raceway 30, which is given a horizontal reciprocating movement by link and lever mechanism 31 into and out of the path of spindle 28. A hopper 32 supplies eyelets to the raceway 30.

The operating means for the foregoing parts may be of any approved design and, as illustrated herein, are for the most part, except as herein described, as shown in said United States Letters Patent No. 1,228,768.

The spindle 28 of the illustrated machine, in order to serve also as an expansible setting tool, is split, as illustrated in Figs. 6 and 9, by a series of longitudinal radial slots 34, illustrated as 8 in number. These slots are closed together at their upper ends 36, as shown in Fig. 9, except during the actual clenching operation when they are spread as in Fig. 6. The upper end of the tool, considered as a whole, is of a gradually tapered or dome-shaped formation, as shown at 38 (Fig. 9), with a clenching surface 40 extending from the portion 42 of maximum diameter in a direction away from the end of the tool. This clenching surface is made up of a group of facets 44 formed upon the members 46 into which the tool is divided by the slots 34. Half-way between each pair of successive slots the clenching surface is formed with a sharp ridge 48 which serves to split the entering end of the eyelet barrel, thus insuring a symmetrical clench. Centrally of the end of the setting tool is an opening 50 (Fig. 2) arranged to receive the conical end 52 (Figs. 4 and 6) of an expander 54 housed within a tubular punch 56 carried by punch bar 16. At the appropriate time in the cycle of operation of the machine, the end 52 of the expander 54 enters the hole 50 in the end of the spindle or setting tool 28, and, by relative movement of the expander 54 and the setting tool 28, springs the members 46 of the setting tool apart bringing the clenching surface 40 into expanded clenching condition between adjacent layers of the work. While the expansible setting tool 28 is maintained in this condition, the eyelet supporting tool 26, with an eyelet resting upon its upper end 27 and surrounding spindle 28, moves upwardly forcing the entering end of the eyelet barrel against the expanded clenching surface 40 and clenching the eyelet, as illustrated in Fig. 6, between adjacent layers of the work. It should be noted that the work in which invisible eyelets are set ordinarily consists of at least three or more layers (the upper leather, the lining or facing, and the eyelet stay), the eyelets passing through the lining or facing and the eyelet stay and being clenched beneath the upper leather, as shown in Fig. 6. On account of the relatively small scale on which Figs. 3, 4 and 5 are drawn, no attempt is made to differentiate between the lining or facing and the eyelet stay in those figures, the disclosure being, in this respect, diagrammatic.

In order to control the punch 56 during the introduction and clenching of the eye-

let, and to prevent damage to the eyelet or to the expansible setting tool 28, means, which will now be described, is provided for at least partially withdrawing punch 56 from the work, after the conclusion of the feeding of the work and before the insertion of the eyelet. For this purpose a collar 58 is secured to punch bar 16, the upper surface of this collar forming a stop co-operating with a stop 60 formed as a lug upon a slide member 62 connected by a screw and slot connection 64 with a slideway 66 formed in a block 68 to which toggle member 20 is pivoted. Block 68 is slidably mounted on punch bar 16, its upward movement being limited by a collar 70 secured thereto. A spring 72 urges stop 60 to the left, as shown in Fig. 3. A spring 74, surrounding the upper portion of punch bar 16, bears at one end in a socket 76 formed in the sliding head 10 and at the other end against a collar 78 secured to the punch bar 16. Spring 74 presses collar 58 against stop 60 when the two are in alinement (as shown in Fig. 3), and when stop 60 is moved to the right (as shown in Fig. 4), out of alinement with collar 58, lifts the punch bar until collar 58 engages the body portion of slide member 62. The distance which the punch bar 16 is thus lifted is enough to withdraw the punch 54 sufficiently to prevent it from interfering with the expansible setting tool 28 during the introduction or clenching of the eyelet.

In order to disengage stop 60 from collar 58 at an appropriate point in the cycle of operation of the machine, slide member 62 is provided with an end surface 80, arranged in alinement horizontally with an adjustable stop member 82 carried by an arm 84 (Fig. 2) secured to raceway 30, and positioned, as the raceway moves to the right after the taking of an eyelet therefrom by the spindle or expansible setting tool 28 and after the conclusion of the feeding movement of the work but before the introduction of the expansible setting tool 28 into the hole in the work, to force slide member 62 to the right, thereby disengaging collar 58 and stop 60 and permitting spring 74 to raise punch 56 a distance somewhat greater than the thickness of the layers of the work through which the eyelet barrel is to pass. Before the return movement of the punch 56 to punching position, toggle 18, 20 is broken and thereby lifts block 68 and slide 62 to such an extent that stop 60 can be moved back by spring 72 into vertical alinement with collar 58, so that when the toggle is again straightened stop 60 and collar 58 will engage each other and punch 56 will be forced down through the work against the surface of punch block 4.

In order to prevent damage to the expansible setting tool 28 by a chip punched from

the work, the expander 54 is made to serve also as a chip ejector. For this purpose it is backed up by a rod 86 (Figs. 3 and 4) housed within punch bar 16 and provided at its upper end with a collar 88 against which engages a spring 90 also housed within punch bar 16 and bearing at its upper end against a plate 92 secured to collar 78 by screws 94. The expander 54 yields against the compression of spring 90 during the punching operation but when, during the feeding movement, the punch 56 passes beyond the end of punch block 4, expander 54 snaps forward under the influence of spring 90 and ejects the chips punched from the work. These are caught in a chip collector 96, shown in detail in Fig. 10, and comprising a trough secured by lugs 98 to the work support 4. This trough is provided with a wall 100 at its side away from the punch block, and with a conduit 102 to which may be attached a pipe or hose 104 to carry off the chips to any suitable receptacle or locality. Wall 100 is provided with a V-shaped notch 106 arranged to permit the passage of the conical end 52 of ejector 54.

In order to control the position of the combined chip ejector and expander 54, a lever 108 is fulcrumed at 110 (Fig. 2) to plate 92. A spring 114 bearing at one end against a lug 116 carried by plate 92 and at the other end against lever 108 urges the latter in a clockwise direction, as viewed in Fig. 2, and thereby tends to hold the forward end of lever 108 in engagement with the upper end of rod 86. Carried by a stationary part of the frame of the machine is a hardened block 118 having a surface 120 arranged for engagement by a roll 122 journaled in lever 108, and arranged, as punch bar 16 moves upwardly under the influence of spring 74 when collar 58 and stop 60 are disengaged, to lock rod 86 and expander 54 against upward movement. This takes place shortly before the end of the feeding movement of the punch 56 and, of course, before the expansible setting tool reaches the expander 54. It results in an accurate, positive positioning of the conical end 52 of expander 54 so as properly to position the clenching surface 44 of the expansible setting tool 28 to clench the eyelet between the layers of the work.

In order to position the work relatively to the expander 54 and expansible setting tool 28, the machine is provided with an abutment, illustrated at 124, provided with a circular opening arranged to receive and surrounding punch 56. Abutment 124 is provided with or carried by an arm 126 pivoted at 128 to a collar 130 mounted for sliding movement on the lower end of punch bar 16. Screw 132 threaded into collar 130 has its entering end received in a slot or groove 133 formed in punch bar 16, this slot being of such dimensions that, except during the return movement of punch bar 16, it permits free move-

ment of collar 130 and abutment 124 relatively to punch bar 16. A spring 134 urges collar 130 downwardly thereby controlling movement of the abutment 124 in a direction away from the work. To limit this downward movement of collar 130, the latter is provided with a pair of lugs 136 (Figs. 1, 2 and 5) engaging the squared shank 137 and the head 138 of a stop screw 140 threaded into a sleeve 142 pivoted at 144 to sliding head 10. During the feeding movement and during the introduction and clenching of the eyelets, abutment 124 is held in its lowermost position by spring 134, lugs 136 engaging against the upper surface of head 138 of screw 140. During the feeding of the work, abutment 124 is located normally just out of engagement with the upper layer of the work, as shown in Fig. 3. When the eyelet is introduced, however, the upward thrust of the eyelet barrel urges the work upwardly into engagement with the lower surface of abutment 124 which thus limits the upward movement of the work and prevents the work from moving beyond its proper position relatively to the clenching surface of the expansible setting tool 28. During the return movement of the punch, punch bar 16 is elevated to such an extent that screw 132 bears against the bottom of slot 133. It is with the punch in this position that the machine comes to rest and when at rest abutment 124 may be swung in a clockwise direction about its pivot 128 to permit the removal and replacement of punch 56, or for any other reason. In order to hold abutment 124 alternatively in operative position or swung to the left, arm 126 houses a spring pressed plunger 146 (Fig. 3) having a conical end arranged to co-operate with either one of a pair of conical openings 148, 150 in collar 130. It will also be observed that when the machine is at rest between operations screw 138 may be swung to the right about pivot 144 and adjusted, if necessary, to position abutment 124 in accordance with the thickness of the stock to be operated upon.

In order to control and to adjust the position of the expansible setting tool when the machine is being set up or when a very radical change is made in the thickness of the work, vertically sliding shaft 24, which is reciprocated by mechanism including a lever 152 connected thereto at 158 (Fig. 1), houses a rod 160 externally threaded at its lower end at 162 to receive a wing nut 164 and a lock nut 165, and internally threaded at its upper end, as shown at 166, to receive a thread formed upon the lower end of the expansible setting tool 28. A spring 168 surrounds the upper portion of rod 160 and bears at its upper end against a collar 169 (Fig. 3) formed upon rod 160, and at its lower end against a surface formed upon a sleeve 170 surrounding spring 168 and threaded into

shaft 24. A set screw 172 threaded into the upper end of sleeve 170 bears against the eyelet supporting tool 26 and prevents its displacement. Thus it will be seen that the supporting tool 26 is rigidly carried by shaft 24 while the expansible setting tool 28 may telescope within shaft 24 against the compression of spring 168. The expansible setting tool 128, however, can never move upwardly beyond the position defined by the adjustment of wing nut 164 and lock nut 165, the upward movement of the latter being positively limited by engagement against a stationary stop 175. Thus it will be seen that the position of the clenching surface 40, when in expanding condition, is positively determined, though adjustable, while the position of the conical end 52 of the expander 54 is also positively determined and serves as the base with respect to which the expansible setting tool 28 is adjustable. It should be understood that once the expansible setting tool has been properly adjusted it will not ordinarily be necessary to adjust it on account of variations in the work since these variations are taken care of by the adjustment of abutment 124.

In the operation of the machine (which comes to rest with the expansible setting tool 28 lowered and the punch 16 and the abutment 124 raised, as shown in Fig. 2), the work is placed upon the work support 2 with the position in which the first eyelet is to be inserted in line with the punch 56, the edge 25 of the work being placed against edge gage 6. Presser foot 8 at this time is also in elevated position. When the machine is started the punch 56 moves down to the position shown in Fig. 3 and punches a hole in the work, the ejector and expander 54 retreating against the compression of spring 90. Then the sliding head 10 moves to the left, punch 56 feeding the work along the work support 2. As punch 56 passes off the punch block 4, ejector 45 54 forces the chips from the punch, the chips being caught by the chip collector 96 and being carried off through conduit 102. At this time abutment 124 is positioned slightly above the work. During this feeding movement the raceway 30 is brought into position so that the endmost eyelet is entered by the expansible setting tool 28, and is received by supporting tool 26, the raceway moving then to the rear and to the right, as viewed in Figs. 55 2 and 4. After the completion of the feeding movement, and before the expansible setting tool 28 has reached the work, the surface 80 of slide 62 is hit by stop 82, as the raceway moves to the right, and stop 60 is moved to the right out of engagement with collar 58. Thereupon, punch bar 16 is lifted by spring 74 and punch 56 is raised so that its end is out of the way of the expansible setting tool, which now enters the hole in the lower 65 layers of the work, finally coming to rest

when lock nut 174 engages stop 175. Continued upward movement of shaft 24 causes eyelet supporting tool 26 to continue its upward movement, the entering end of the eyelet entering the hole in the lower layers of the work and coming into engagement with clenching surface 40 of expansible setting tool 28. The clenching surface 40 at this time is in expanded condition since the setting tool 28 is expanded by the conical end 52 of expander 54 at the time it completes its upward movement, and upward movement of the work is limited by abutment 124. At this time upward movement of the expander 54 is prevented because the roll 122 is in engagement with the surface 120 of the block 118. Continued upward movement of the eyelet supporting tool 26 forces the end of the eyelet barrel against the clenching surface of the expansible setting tool 28, and causes the eyelet to be clenched between the layers of the work, as shown in Fig. 6. Then shaft 24 starts down and toggle 18, 20 is broken, elevating the punch bar which carries with it the punch 56, expander 54, and abutment 124. Raceway 30 also moves to the left permitting spring 72 to move slide 62 so as to bring stop 60 into alignment with collar 58 ready for the next punching operation. At the conclusion of the clenching operation presser foot 8 is moved downwardly into engagement with the work, holding it against inadvertent movement during return movement of the punch to punching position.

Having described my invention, what I claim as new and desire to secure by Letters Patent of the United States is:

1. A machine for inserting barreled fasteners in a plurality of layers of material and clenching the ends of the fastener barrels between adjacent layers of the material having, in combination, a tubular punch arranged to be introduced into the work from one side to punch a hole in the work to receive a fastener, a setting tool arranged to be introduced in the hole from the other side of the work and having an expansible clenching surface operative to clamp the barrel of a fastener between layers of the work, and means housed within the punch operative to expand the setting tool into fastener-clenching condition.

2. A machine for inserting barreled fasteners in a plurality of layers of material and clenching the ends of the fastener barrels between adjacent layers of the material having, in combination, a tubular punch arranged to be introduced from one side of the work to punch a hole therein to receive a fastener, a plunger housed within the punch, an expansible setting tool arranged to be introduced from the other side of the work and provided with a clenching surface arranged upon the expansion of the tool to clamp the barrel of a fastener between the layers of the

- work, and means arranged to cause relative lengthwise movement of the plunger and the setting tool thereby expanding the tool to fastener-clenching condition.
3. An eyelet-inserting machine having, in combination, a tubular punch operable to punch a hole in which an eyelet may be set in a work piece, an expansible setting tool provided with an eyelet-clenching surface arranged when in expanded condition to clench an eyelet between adjacent layers of the work, and a plunger housed within the punch and arranged to expand the expansible tool with its clenching surface between the layers of the work.
4. An eyelet-inserting machine having, in combination, an eyelet-supporting tool, an expansible setting tool housed therein and provided with an eyelet-clenching surface arranged when in expanded condition to clench an eyelet between adjacent layers of material by relative movement of the two tools, a punch operable to punch a hole in the work in which an eyelet may be set, and a plunger housed within the punch and arranged to expand the expansible tool with its clenching surface between the layers of the work.
5. An eyelet-inserting machine having a punch, means for operating the punch to cause the latter to punch an eyelet-receiving hole in the work and to feed the work, a raceway, an eyelet-supporting tool, and an expansible setting tool telescoping therein and arranged to take an eyelet from the raceway and to guide it to eyelet-inserting position, said tools being arranged so that relative movement thereof causes the entering end of the eyelet barrel to be clenched between adjacent layers of the work.
6. An eyelet-inserting machine having a raceway, a punch, means for operating the punch to cause the latter to punch an eyelet-receiving hole in the work and to feed the work, an expansible setting tool arranged to take an eyelet from the raceway and to guide it to eyelet-inserting position, and means housed within the punch arranged so that relative movement of the expansible setting tool and said means causes the expansion of the setting tool to put it in condition to clench the entering end of an eyelet barrel between adjacent layers of the work.
7. A machine for inserting barreled fasteners in a plurality of layers of material and clenching the ends of the fastener barrels between adjacent layers of the material having, in combination, a tubular punch arranged to punch fastener-receiving holes in the work, an expansible setting tool arranged when expanded to clench the entering end of a fastener barrel between adjacent layers of the material, and a combined chip ejector and setting tool expander housed within the tubular punch.
8. A machine for inserting barreled fas-
- teners in a plurality of layers of material and clenching the entering ends of the fastener barrels between adjacent layers of the material having, in combination, a tubular punch arranged to punch fastener-receiving holes in the work, an expansible setting tool arranged to enter the holes formed by the punch and when expanded to clench the entering ends of fastener barrels between adjacent layers of the material, and a combined chip ejector for said tubular punch and expander for said setting tool.
9. A fastener-inserting machine having a tubular punch arranged to form fastener-receiving holes in the work, an expansible setting tool having a plurality of parts arranged when expanded to clench the entering end of a fastener barrel between the layers of the work, and an expander housed within the tubular punch provided with a conical end arranged to be forced between the parts of the expansible setting tool to bring said tool into clenching condition.
10. A fastener-inserting machine having a punch, means for operating the punch to cause the latter to punch a fastener-receiving hole in the work and then to feed the work, and an expansible setting tool arranged to set a fastener in the hole thus punched in the work.
11. An eyelet-inserting machine having a punch, means for operating the punch to cause the latter to punch an eyelet-inserting hole in the work and to feed the work, and an expansible setting tool arranged to guide an eyelet into the hole thus punched in the work and to clench the barrel of the eyelet between adjacent layers of the work.
12. An eyelet-inserting machine having a punch, means for operating the punch to cause the latter to punch an eyelet-receiving hole in the work and to feed the work, an eyelet-supporting tool, an expansible setting tool co-operating therewith, and means for operating said tools to insert an eyelet in the hole formed by the punch and to clench the barrel of the eyelet between adjacent layers of the work.
13. A fastener-inserting machine having an expansible setting tool, an expander therefor arranged so that relative movement of the expander and the setting tool will bring the clenching surface of the tool into fastener-clenching condition, and means positively to lock the expander against retracting movement during the introduction of the expansible setting tool into operative position and during the clenching of the fasteners by the expansible setting tool.
14. A fastener-inserting machine having an expansible setting tool, an expander arranged so that relative movement of the expander and the setting tool will expand the setting tool and thereby will bring its clenching surface into clenching condition, and a

- stationary stop arranged positively to prevent further movement of the setting tool toward the expander when said tool has reached clenching condition.
15. A fastener-inserting machine having an expansible setting tool, an expander arranged so that relative movement of the expander and the setting tool will bring the clenching surface of the setting tool into fastener-clenching condition, and separate means for positively preventing further movement of both the expansible setting tool and the expander when the clenching surface of the setting tool has been brought into clenching condition.
16. A machine for inserting invisible eyelets having, in combination, an expansible setting tool, an expander arranged so that relative movement of the tool and the expander will expand the tool into fastener clenching condition, and a locking member arranged positively to hold the expander in expanding relation to the tool from a time beginning prior to the engagement between the expansible setting tool and the expander and extending through the completion of the clenching in each cycle of operation of the machine.
17. A fastener-inserting machine having, in combination, an expansible set, an expander therefor movable in the direction of feed during the feeding of the work to a position in alinement with the expansible set at the conclusion of the feeding movement, a spring tending to urge said expander toward the work during the feeding movement of the work, a lever arranged for limited rocking movement about its fulcrum, a connection from the lever to the expander, and means for locking the lever in position positively to hold the expander in setting tool expanding position prior to engagement between the expansible set and the expander and during the clenching of a fastener.
18. A fastener-inserting machine having, in combination, an expansible setting tool, an expander therefor movable in the direction of feed during the feeding of the work to a position in alinement with the setting tool at the conclusion of the feeding movement, a spring tending to urge said expander toward the work during the feeding movement of the work, a rod contacting at one end with the expander, a lever contacting at the other end with said rod and arranged for limited rocking movement about its fulcrum, a spring tending to rock said lever into engagement with said rod, and means for locking the lever in position to hold the rod and expander in setting tool expanding position during the clenching of a fastener.
19. A fastener-inserting machine having, in combination, an expansible setting tool provided with a plurality of radial slots extending lengthwise of the tool at one end
- thereof, the members formed by said slots being provided with facets adjacent to the end of the set and together forming a clenching surface, the end of the set beyond said clenching surface being of a dome shape with a central cavity therein, a tubular punch, and an expander housed within the punch and having a conical end portion arranged by relative movement of the expander and the setting tool to be inserted in the cavity at the end of the tool and by continued relative movement to expand the tool, thereby bringing the tool into clenching condition.
20. A fastener-inserting machine having an expansible set, a tubular punch, a combined chip ejector and setting tool expander housed within the punch, means for moving the punch transversely to feed the work from punching to fastener-inserting position, means arranged to move the ejector lengthwise of the punch and operative to cause the ejector to force a chip from the punch during the feeding of the work, and mechanism unlocked during the feeding movement to permit movement of the ejector and locked after the conclusion of the feeding movement to hold the ejector in setting tool expanding position during the clenching of the fastener.
21. A fastener-inserting machine having an expansible setting tool, a tubular punch, a combined chip ejector and setting tool expander housed within the punch, means for moving the punch transversely to feed the work from punching to fastener-inserting position, a spring tending to move the ejector lengthwise of the punch and operative to cause the ejector to force a chip from the punch during the feeding of the work, and mechanism unlocked during the feeding movement to permit spring control of the ejector and locked after the conclusion of the feeding movement to hold the ejector in setting tool expanding position during the clenching of the fastener.
22. A machine for inserting eyelets and clenching the entering ends of their barrels between adjacent layers of material having, in combination, work-punching, eyelet-clenching, and work-feeding tools, a punch bar carrying said punching tool, an abutment carried by said punch bar and arranged to limit the movement of the work under the thrust of the eyelets inserted, connections between said abutment and said punch bar arranged to permit a limited amount of relative movement of the abutment and punch bar, means for controlling said abutment comprising a stop arranged to limit movement of the abutment toward the work and a spring surrounding said punch bar and tending to urge said abutment toward said stop, a second spring tending to move the punch bar away from the work, stop mechanism arranged to prevent movement of the

punch away from the work during the feeding movement, and means operative after the work has been fed to eyelet inserting position to cause said stop mechanism to permit 5 movement of said punch away from the work under the actuation of said second-named spring to a predetermined position prior to the insertion of each fastener.

23. A machine for inserting eyelets and 10 clenching the entering ends of their barrels between adjacent layers of material having, in combination, work-punch, eyelet-inserting, and work-feeding means, a raceway, means for moving said raceway to supply eyelets to 15 the eyelet-inserting means, a punch bar carrying said punching means, an abutment carried by said punch bar and arranged to limit the movement of the work under the thrust of the eyelets inserted, means for controlling 20 said abutment comprising a spring tending to urge the abutment toward the work and a stop limiting the movement of the abutment toward the work, a connection between said abutment and said punch bar permitting a 25 limited amount of relative movement of the abutment and punch bar, a second spring tending to move the punch bar away from the work, stop mechanism arranged to prevent movement of the punch bar away from 30 the work during the feeding movement, and means including a member movable with the raceway and operative by the raceway movement after the work has been fed to eyelet-inserting position to cause said stop mechanism to permit movement of the punching tool away from the work under the actuation of said second-named spring to a predetermined position prior to the insertion of each 35 fastener.

40 24. A fastener-inserting machine having a punch bar, a punch carried thereby arranged to punch a hole in the work and feed the work to fastener-inserting position, fastener-inserting instrumentalities, an abutment 45 carried by the punch bar and arranged for limited movement lengthwise thereof, a stop member fixed against movement toward and from the work during the operation of the machine, a connection between said stop and 50 the abutment whereby movement of the abutment in the direction of the work is positively limited by said stop member, a spring tending to urge the abutment toward the work and limited in that tendency by said stop member, another spring tending to move the punch bar away from the work, stop mechanism arranged to prevent such movement of the punch bar away from the work during 55 the feeding movement, and means operative at the conclusion of the feeding movement to cause said stop mechanism to permit the punch bar to have limited movement in a direction away from the work to a predetermined extent under the actuation of said last-named spring.

25. A fastener-inserting machine having a punch bar, a punch carried thereby arranged to punch a hole in the work and feed the work to fastener-inserting position, fastener-inserting instrumentalities, a raceway arranged to supply fasteners to said instrumentalities, an abutment carried by the punch bar and arranged for limited movement lengthwise thereof, an adjustable stop member fixed against movement toward and from the work during the operation of the machine, a connection between said stop and the abutment whereby movement of the abutment in the direction of the work is positively limited by said stop member, a spring tending to urge the abutment toward the work and limited in that tendency by said stop member, another spring tending to move the punch bar away from the work, stop mechanism arranged to prevent such movement of the punch bar away from the work during the feeding movement, and means including a member carried by said raceway operative at the conclusion of the feeding movement to cause said stop mechanism to permit the punch bar to have limited movement in a direction away from the work to a predetermined extent under the actuation of said last-named spring.

26. A machine for inserting barreled fasteners and clenching the entering ends of their barrels between adjacent layers of material having, in combination, a punch, fastener-inserting and clenching instrumentalities, an abutment arranged to control the position of the work relatively to said instrumentalities, a raceway, means for moving the raceway into and out of engagement with one of said fastener-inserting instrumentalities to supply fasteners thereto, stop mechanism arranged to prevent movement of said punch in a direction away from the work comprising two members one of which is mounted for movement relatively to the other, and a member carried by said raceway and movable therewith arranged for contact with one of said stop members thereby to cause the stop mechanism to permit movement of the punch in a direction away from the work to a predetermined position.

27. A fastener-inserting machine having, in combination, a punch, instrumentalities for inserting fasteners and clenching the entering ends of their barrels between adjacent layers of material, an abutment arranged to control the position of the material relatively to said fastener-inserting instrumentalities, and stop mechanism arranged to prevent movement of the punch away from the work during the feeding of the work to fastener-inserting position and to permit limited movement of the punch to a predetermined position relatively to the contacting surfaces of the layers of material between which the fasteners are clenched prior to the clenching of each fastener.

28. A fastener-inserting machine having, in combination, a punch, instrumentalities for inserting fasteners and clenching the entering ends of their barrels between adjacent layers of material, a raceway arranged to supply fasteners to said inserting instrumentalities, an abutment arranged to control the position of the material relatively to said fastener-inserting instrumentalities, stop mechanism arranged to prevent movement of the punch away from the work during the feeding of the work to fastener-inserting position, and a member carried by the raceway operative on the stop mechanism to cause the latter to permit limited movement of the punch to a predetermined position relatively to the contacting surfaces of the layers of material between which the fasteners are clenched prior to the clenching of each fastener.
29. A machine for inserting barreled fasteners in a plurality of layers of material and clenching the ends of the fastener barrels between adjacent layers of the material having, in combination, an expansible setting tool, a punch, operating means arranged to cause the punch to punch a fastener-receiving hole in the work and thereafter to feed the work to fastener-inserting position, means for withdrawing the punch after the work has been fed to fastener-inserting position sufficiently to prevent interference by the punch with the fastener-inserting and clenching operations, and operating means for the expansible setting tool arranged to cause said tool to clench a fastener between adjacent layers of the work.
30. A machine for inserting eyelets in a plurality of layers of material and clenching the entering ends of their barrels between adjacent layers of the material having, in combination, a punch, means for operating the punch arranged to cause the latter to punch an eyelet receiving hole in the work and then to feed the work, an expansible setting tool arranged to guide an eyelet to the hole thus punched in the work and to clench the entering end of its barrel between adjacent layers of the work, and means for withdrawing the punch sufficiently to prevent interference by the punch with the introduction and clenching of the eyelet in the work.
31. A machine for inserting eyelets in a plurality of layers of material and clenching the entering ends of their barrels between adjacent layers of the material having, in combination, a punch, means for operating the punch to cause the latter to punch an eyelet receiving hole in the work and then to feed the work, an eyelet supporting tool, an expansible setting tool co-operating therewith, means for operating said tools to insert an eyelet in the hole formed by the punch and then to clench the barrel of the eyelet between adjacent layers of the work, and means operated after the completion of the feeding of the work and prior to the clenching of the eyelet to withdraw the punch sufficiently to prevent interference by the punch with the clenching of the eyelet.
32. A machine for inserting eyelets in a plurality of layers of material and clenching the entering ends of their barrels between adjacent layers of the material having in combination, a punch, means for operating the punch to cause the latter to punch an eyelet receiving hole in the work and then to feed the work, an expansible setting tool, an expander arranged to expand the setting tool and thereby to bring it into eyelet clenching condition, means co-operating with the setting tool arranged to introduce an eyelet into the hole in the work and to cause the expanded setting tool to clench the entering end of the barrel of the eyelet between adjacent layers of the work, and means operating after the conclusion of the feeding movement of the punch and before the introduction of the eyelet for withdrawing the punch sufficiently to prevent interference with the clenching of the eyelet.
33. A fastener-inserting machine having an expansible setting tool, a tubular punch, and an expander for said tool housed within the punch and, as the work is fed toward fastener-inserting position, first operating to eject the chips cut from the work by the punch and later locked in position to expand the expansible set.
34. A fastener-inserting machine having an expansible setting tool, a tubular punch, an expander for said tool housed within the punch and operating as the work is fed toward fastener-inserting position first to eject the chips cut from the work by the punch and later locked in position to expand the expansible set, and means for moving the expansible set into engagement with the expander, to expand said tool to clenching condition.
35. A fastener-inserting machine having a punch block, a tubular punch co-operating therewith, means for moving the punch into engagement with the punch block to punch a fastener-receiving hole in a work piece resting upon the punch block, means for moving the punch along the surface of the punch block to bring the hole to fastener-inserting position, an ejector arranged to force from the punch the chips cut from the work by the punch, and means for inserting a fastener in the hole formed in the work piece by the punch.
36. A fastener-inserting machine having a punch block, a tubular punch co-operating therewith, means for moving the punch into engagement with the punch block to punch a fastener-receiving hole in a work piece resting upon the punch block, means for moving the punch along the surface of the punch

block to feed the work to fastener-inserting position, an ejector housed within the punch, means for moving the ejector lengthwise of the punch to force out the chips cut from the work by the punch, and means for inserting a fastener in the hole formed in the work piece by the punch.

37. A fastener-inserting machine having a punch block, a tubular punch co-operating therewith to punch a fastener-receiving hole in the work, means for moving the punch along the surface of the block to feed the work toward fastener-inserting position, an ejector housed within the punch, means arranged to cause the ejector to eject the chips cut by the punch from the work, and a setting tool arranged to insert a fastener in the hole formed in the work by the punch and to clinch its entering end upon a surface of a layer of the work.

38. A fastener-inserting machine having a punch block, a punch co-operating therewith, means for moving the punch toward the punch block to punch a fastener-receiving hole in the work, means for moving the punch along the punch block to feed the work to fastener-inserting position, a spring-pressed ejector arranged to force the chips from the punch when the latter moves beyond the edge of the punch block, and a setting tool arranged to insert a fastener in the hole formed in the work by the punch and to clinch its entering end upon a surface of a layer of the work.

39. A fastener-inserting machine having a punch block, a tubular punch co-operating therewith, means for moving the punch toward the punch block to punch a fastener-receiving hole in the work, means for moving the punch along the punch block to feed the work to fastener-inserting position, a spring-pressed ejector housed within the punch and arranged to force the chips from the punch when the latter moves beyond the edge of the punch block, and a setting tool arranged to insert a fastener in the hole formed in the work by the punch.

40. A fastener-inserting machine having a punch block, a punch co-operating therewith to punch fastener-receiving holes in the work and movable along the surface of the block to feed the work toward fastener-inserting position, an ejector housed within the punch and arranged to eject the chips as the punch moves beyond the edge of the punch block, a chip collector adjacent to the punch block comprising a trough arranged to receive the ejected chips and to conduct them from fastener-inserting position, and means for inserting fasteners in the holes punched in the work by the punch.

41. A fastener-inserting machine having a punch arranged to punch a hole in a work piece and to feed the work piece to fastener-inserting position, a chip ejector arranged to

70 eject the chips cut from the work, a chip collector arranged to receive the ejected chips comprising a trough having a wall provided with an opening to permit the passage of the end of the ejector as the work is fed, and a setting tool arranged to insert a fastener in the hole formed in the work by the punch.

42. A fastener-inserting machine having a punch block, a tubular punch co-operating therewith and arranged to punch a hole in a work piece and to feed the work piece to fastener-inserting position, a chip ejector housed in the punch and arranged to eject the chips cut from the work, a chip collector adjacent to the punch block arranged to receive the ejected chips comprising a trough having a wall provided with an opening to permit the passage of the end of the ejector as the work is fed, and a setting tool arranged to insert a fastener in the hole formed in the work by the punch.

43. A machine for operating on sheet material having a tubular punch, a chip ejector housed therein, and a chip collector arranged to receive the ejected chips and to conduct them away.

44. A fastener-inserting machine having a punch arranged to punch fastener-receiving holes in a work piece, an ejector arranged to eject chips punched from the work piece by the punch, a chip collector arranged to receive the ejected chips and to conduct them from the fastener-inserting locality, and means for inserting fasteners in the holes formed by the punch in the work.

45. A machine for operating on sheet material having a punch block, a punch co-operating therewith, an ejector arranged to eject from the punch the chips punched from the work, and a chip collector adjacent to the punch block and arranged to receive the chips as they are ejected from the punch and to conduct them from the punching locality.

46. A machine for operating on sheet material having a punch block, a tubular punch co-operating therewith, an ejector housed therein and arranged to eject the chips punched from the work, and a chip collector adjacent to the punch block and provided with a conduit arranged to receive the ejected chips and to conduct them from the punching locality.

47. A machine for inserting invisible eyelets having, in combination, work punching and eyelet clenching tools, an abutment arranged to limit movement of the work under the thrust of the eyelets inserted, and means for controlling the punching tool comprising a spring tending to move the punching tool away from the work, stop mechanism arranged to prevent such movement of the punching tool, and means operative after the work has been fed to eyelet inserting position to cause such stop mechanism to permit said spring to move the punching tool to a

predetermined position prior to the insertion of each eyelet.

48. A machine for inserting invisible eyelets having, in combination, work punching, eyelet clenching and work feeding tools, an abutment arranged to limit movement of the work under the thrust of the eyelets inserted, means for controlling said abutment comprising a spring tending to move the abutment toward the work, a spring tending to move the punching tool away from the work, stop mechanism arranged to prevent movement of the punching tool away from the work during the feeding movement, and means operative after the work has been fed to eyelet inserting position to cause said stop mechanism to permit movement of said punching tool to a predetermined position under the actuation of said second-named spring prior to the insertion of each fastener.

49. A fastener-inserting machine having, in combination, fastener inserting means, work feeding means having work feeding and return movements, work-controlling means comprising a support fixed against movement toward and from the work, an abutment movable with the work feeding means and adjustable toward and from the work, means for holding the abutment out of engagement with the work during the return movement of the work feeding means, and means carried by said support arranged positively to limit movement of the abutment toward the work.

50. A machine for inserting barreled fasteners in a plurality of layers of material and clenching the entering ends of the fastener barrels between adjacent layers of the material having, in combination, a setting tool provided with a fastener-clenching surface arranged to be introduced between the layers of material to clench the entering end of a fastener barrel between adjacent layers, an abutment member arranged to limit movement of the work under the thrust of the entering end of the fastener barrel, a spring arranged to hold the abutment member in engagement with the work during the insertion of fasteners, and an adjusting screw for the abutment member against which a portion of the abutment is held by the spring during the insertion of the fasteners arranged by rotation to vary the position at which the abutment is held relatively to the clenching surface of the tool during the clenching of the fasteners.

51. A fastener-inserting machine having work-controlling means comprising an abutment, a spring urging the abutment toward the work, means for holding the abutment in engagement with the work during the insertion of each fastener and for withdrawing it from the work after the insertion of each fastener, a stop for positively limiting the movement of the abutment toward the work

under the influence of said spring, and means for varying the position of the stop thereby adjusting the position taken by the abutment under the action of the spring.

52. A fastener-inserting machine having work-controlling means comprising an abutment, means for moving the abutment into and out of engagement with a work piece including a spring urging the abutment toward the work piece, a stop for positively limiting the movement of the abutment toward the work piece under the influence of the spring, and a screw rotatable to vary the position of said stop and thereby to adjust the position taken by the abutment under the action of the spring.

53. A machine for inserting invisible eyelets having a punch arranged to punch a hole in the work to receive an eyelet, a support fixed against movement toward and from the work, an abutment adjacent to the punch arranged to control movement of the work in the direction of the length of the punch, a screw connected to the support and to the abutment and arranged by its rotation to vary the work controlling position of the abutment lengthwise of the punch, and means for introducing the barrel of an eyelet in the hole formed by the punch in the work and clenching the entering end of the eyelet barrel between adjacent layers of the work.

54. A fastener-inserting machine having a punch bar, a punch carried thereby arranged to punch a fastener-receiving hole in the work, a support fixed against movement in the direction of the work, an abutment carrier mounted upon the punch bar, an abutment carried by said carrier to limit movement of the work lengthwise of the punch, cooperating means carried by said support and abutment carrier arranged to control movement of the abutment in both directions lengthwise of the punch bar and means for introducing the barrel of an eyelet in the hole formed by the punch in the work and clenching the entering end of the eyelet barrel between adjacent layers of the work.

55. A fastener-inserting machine having a reciprocating bar, an abutment carrier mounted thereon, means for periodically reciprocating the bar, once during each cycle of operation of the machine, an abutment carried by said carrier and moved into and out of engagement with a work piece by the reciprocation of the bar, means for positively limiting movement of the abutment in the direction of the work, and means for controlling movement of the abutment in the opposite direction.

56. A fastener-inserting machine having a reciprocating bar, an abutment carrier mounted thereon, means for periodically reciprocating the bar, once during each cycle of operation of the machine, an abutment carried by the abutment carrier and moved

into and out of engagement with a work piece by the reciprocation of the bar, an adjustable stop arranged positively to limit the movement of the abutment in the direction of the work, and a spring for controlling the movement of the abutment in the opposite direction.

57. A machine for inserting blind and invisible eyelets having in combination a reciprocating bar, an abutment carrier mounted thereon, an abutment pivoted to said abutment carrier for movement into and out of operative position and arranged when in operative position to engage a work piece during the insertion of each fastener and to be withdrawn after the insertion of each fastener, and means for holding the abutment alternatively in either operative or inoperative position.

58. A fastener-inserting machine comprising a tool carrier, a fastener inserting tool carried thereby, an abutment pivotally connected to the tool carrier for movement into and out of operative position and arranged to limit movement of the work relatively to the fastener inserting tool during the insertion of each fastener, and means for holding the abutment alternatively in either operative or inoperative position.

59. A fastener-inserting machine having, in combination, a punch carrier, a punch carried thereby arranged to punch fastener-receiving holes in the work, an abutment carrier secured to the punch carrier, an abutment pivoted to the punch carrier for movement into and out of operative position, and arranged when in operative position to position the work for the inserting of a fastener, and means for inserting a fastener in the hole formed by the punch while the work is positioned by the abutment.

60. An expandible setting tool for an eyelet-inserting machine having a clenching surface comprising a plurality of facets each formed on one of a plurality of radially movable members arranged to enter from the flange end of an eyelet barrel and terminating in the plane of maximum diameter of the eyelet receiving and clenching portion of the tool, the entering end of said tool being tapered to facilitate its entrance into a fastener-receiving hole and the clenching surface thereof extending from the plane of maximum diameter of the eyelet receiving and clenching portion of the tool in a direction away from the end of the tool.

61. An expandible setting tool for a fastener-inserting machine having a clenching portion adjacent to its extreme entering end, its centering end being of less than the maximum diameter of its clenching portion, and having its clenching surface extending from the plane of maximum diameter away from the entering end.

62. An expandible setting tool comprising an elongated member with a plurality of radial slots extending lengthwise of the tool at one end thereof, the members formed by said slots being provided with facets forming a clenching surface extending from the portion of maximum diameter away from the end of the tool, and with the end of the tool beyond said clenching surface of a gradually reduced diameter.

63. An expandible setting tool comprising an elongated member with a plurality of radial slots extending lengthwise of the set and closed together toward one end thereof, the members formed by said slots being provided with facets forming a clenching surface extending from the portion of maximum diameter away from said end of the setting tool, and with the end of the tool beyond said clenching surface tapered toward its entering end.

64. An expandible setting tool for a fastener-inserting machine provided with a plurality of radial slots extending lengthwise of the tool at one end thereof, the members formed by said slots being provided with facets adjacent to the end of the set and together forming a clenching surface, the end of the set beyond said clenching surface being of a dome shape with a central cavity therein the dome-shaped end and the clenching surface intersecting at the portion of maximum diameter of the slotted end of the tool.

In testimony whereof I, the said FRED A. RUMNEY, have signed my name to this specification.

FRED A. RUMNEY.

In testimony whereof I, the said ALBERT E. HUDSON, have signed my name to this specification.

ALBERT E. HUDSON.
